DIVERSITY RECEIVER

John B. Moore, Riverhead, N. Y., assignor to
Radio Corporation of America, a corporation of
Delaware

Application February 20, 1936, Serial No. 64,801

6 Claims. (Cl. 250—20)

My present invention relates to the general improvement of diversity radio receivers.

Diversity receivers have proven especially successful for the reduction of fading—an undesirable phenomenon experienced during the reception of signals transmitted on short radio waves. These receivers usually make use of a multiplicity of separated antennae whose currents either before or after rectification are combined to operate a single translating device. However, diversity arrangements as heretofore known are, as far as I am aware, limited in flexibility.

Since flexibility is an extremely desirable characteristic in the toll communications field, the prime object of my present invention is to provide a highly flexible diversity receiving system which may be used for telegraphic or telephonic signals, or which may be used to provide separate signals of the telephonic or telegraphic type or which may be used to provide, simultaneously, separate signals some of which result from partial employment of full diversity receiving apparatus. Other objects, advantages and features of my present invention will become apparent as the more detailed description thereof proceeds.

Turning to the accompanying drawings, which are only illustrative of my present invention:

Figures 1 to 4 are block diagrams generally illustrative of my present invention;

Figure 5 schematically illustrates in somewhat greater detail the radio frequency and intermediate frequency units of Figures 1 to 4 inclusive;

Figure 6 illustrates the signal control circuits of my present invention which are utilized in a manner to be described more fully hereinafter;

Figure 7 is a wiring diagram of an audio frequency amplifier which may be used in connection with my present invention;

Figure 8 is a wiring diagram of a tone keying system useful in connection with my present invention; and

Figure 9 illustrates a monitoring arrangement which may be used in my present diversity receiving system.

In the diversity receiving system which I am about to describe in greater detail, it has been found that three receivers have proven most practicable from the point of view of performance and economics. Additional receivers will, of course, add to the improvement in reception, but are not essential.

With the system herein disclosed, the three

receivers may be utilized:—to supply three separate telephone signals; to provide a diversity arrangement of three receivers; to supply a single telephonic signal or a single telegraphic signal; or to connect two receivers on either type of service, making the third receiver available for another signal. By a slight re-arrangement, three separate and different telegraphic signals may be received.

Figure 1 shows the general rack layout of the apparatus utilized in my improved diversity receiving system. The radio frequency apparatus RF for each receiver is placed on top. The radio frequency apparatus of each receiver is provided with separate tubes and circuits for each of three distinct frequency bands, the antenna transmission line plugs for which are indicated at P1—1, P1—2, P1—3, P2—1, P2—2, P2—3, P3—1, P3—2 and P3—3. Beneath the radio frequency stages RF—1 are placed, as indicated, the power control apparatus PC, audio frequency amplifier AF—1, intermediate frequency apparatus IF—1 and diode detection apparatus DD—1. The apparatus beneath the radio frequency stages RF—2 is quite similar with the exception of the provision of signal control apparatus SC which shall be described in greater detail hereinafter.

Beneath the radio frequency stages RF—3 are mounted two tone keyers and oscillators TKO—1 and TKO—2. If desired, either of these tone keyers and oscillators may be replaced by an audio frequency amplifier such as AF—1 and AF—2. Various input, automatic gain control, and monitoring output circuits are provided, as indicated, and will be described in greater detail hereinafter.

Figures 2, 3, and 4 diagrammatically illustrate some of the combinations obtainable with my improved diversity receiving apparatus, by manipulation of the switches on the signal control panel SC of Figure 1.

In Figure 2 the three receivers are shown connected in full diversity fashion for either telephony or telegraphy. In Figure 3, two of the receivers are combined to give diversity telephony or telegraphy reception and the other receiver is left free for either telegraphy or telephony; and in Figure 4, the three receivers are arranged so as to produce three separate signals.

Figure 5 shows in greater detail, although in block diagram form, the apparatus contained within the radio frequency units and intermediate frequency units of Figure 1. The antenna

plugs $P1-1$, $P1-2$ and $P1-3$ may be connected to antennae separately suited for different radio frequency bands such as, respectively, three to six megacycles, six to twelve megacycles and twelve to twenty-four megacycles. These bands are chosen simply by way of illustration and are not to be considered in any way as limiting the present invention. The output of block $P1-1$ is fed successively through the antenna tuning stage $AT1-1$ and radio frequency tuning stages $RFT1-1$ and $RFT1-2$. These stages are provided with as many tubes, tuning circuits and individual controls or, if desired, uncontrolled controls as found desirable. The output of the radio frequency tuning stage $RFT1-2$ is fed to the tube detector stage $TD1-1$ which is also supplied with oscillations from the local oscillator $LO1-1$. All of this apparatus, including independent tubes in the amplifier, detector and oscillator stages are duplicated beneath the plugs $P1-2$ and $P1-3$ with, of course, suitable adjustments in the circuits to make them suitable for operation on the other frequency bands chosen. The radio frequency filament switch RFS selectively energizes the filaments of all tubes under each plug. With the switch arms in their upper position, all tubes under plug $P1-1$ will be energized, thereby receiving signals to which the three to six megacycle band system is tuned. With the switch arms in the middle position, signals may be received on the channel or frequency band to which the circuits under plug $P1-2$ are adjusted, etc. As shown, the detectors $TD1-1$, $TD1-2$ and $TD1-3$ have their outputs connected in parallel and all channels are beat down by suitable tuning of the local oscillators, $LO1-1$, $LO1-2$ and $LO1-3$ to a common intermediate frequency such as three hundred kilocycles.

40 The apparatus of the unit $RF1$ (Figure 5) is duplicated in the units $RF2$ and $RF3$ of Figure 1, all of the outputs of which are beat down, as shown in Figure 5, to, for example, a common intermediate frequency such as three hundred 45 kilocycles.

Intermediate frequency energy is fed separately, as shown in Figure 5, to the intermediate frequency units $IF1$, $IF2$ and $IF3$ which are identical in structure. Consequently, only unit $IF1$ 50 will be described in detail.

The intermediate frequency output of unit $RF1$ is fed to a two stage tuned intermediate frequency amplifier $TIFA1$ whose output in turn is fed to the IF detector $IFD-1$. This hetero-55 dyne detector or frequency converter stage is supplied from the intermediate frequency local oscillator $IFLO$.

The output of the intermediate frequency detector $IFD-1$ is adjusted to some suitable value 60 such as fifty kilocycles and fed through the intermediate frequency transformer $IFT-1$ to two intermediate frequency amplifier units $NFA-1$ and $WFA-1$. Each of these fifty kilocycle amplifiers $NFA-1$ and $WFA-1$ are suitably tuned 65 and are provided with a suitable number of tubes to provide for desired amplification of the waves supplied thereto. These amplifier stages, however, differ in that amplifier $NFA-1$ passes a narrower band of frequencies and is adapted 70 for telegraphy as it tends to reduce noise level and eliminate interference from adjacent channels, whereas intermediate frequency amplifier $WFA-1$ has a broader frequency characteristic and is particularly suited for telephony since 75 it will tend to cause reproduction of the trans-

mitted signal with high fidelity. These amplifiers are selectively put into circuit by the selective switch NWS whose switch arms when in their upper position cause energization of the cathodes of the narrow intermediate frequency 5 amplifier $NFA-1$ and in their lower position de-energize the cathodes of $NFA-1$ and cause heating of the cathodes of the wide pass band amplifier $WFA-1$.

The outputs of the amplifiers $NFA-1$ and $WFA-1$ are fed to a common push-pull diode detector $DD-1$ whose output is taken off at point X . Similarly, the outputs of diode detectors $DD-2$ and $DD-3$ of the intermediate frequency units $IF-2$ and $IF-3$ are taken from 15 points Y and Z respectively.

The connections X , Y , Z of Figure 5 are brought to the signal control panel SC of Figure 1 which is illustrated in greater detail in Figure 6. As shown in Figure 6, the diode detector outputs of $DD-1$, $DD-2$ and $DD-3$ are connected respectively to the signal indicators or milliammeters $MA-1$, $MA-2$ and $MA-3$. The output conductor 2 of indicator $MA-1$ is connected to the switches $1A$ and $1B$; the output conductor 4 of signal indicator $MA-2$ is connected as indicated to the switches $2A$ and $2B$, and the output conductor 6 of $MA-3$ is connected to the switches $3A$ and $3B$.

For a full diversity telegraphy connection, 30 switches $1B$, $2B$ and $3B$ are thrown to their down position so that the following contacts are closed: $1B1$, $1B2$, $2B1$, $2B2$, $3B1$ and $3B2$. With these connections made, it will be found that the detected outputs of the three receivers are combined in the conductor 8 which is fed to a tone keyer such as the tone keyer $TKO-1$ of Figure 1 and which shall be described in greater detail hereinafter.

To indicate the combined output in indicator $MA-4$, contacts $4B1$ and $4B2$ are closed. Normally, contacts $4BN1$ and $4BN2$ are closed. Automatic gain control supply voltage for the radio frequency units $RF1$, $RF2$ and $RF3$ is brought in from conductor 10 and is fed back to 45 the radio frequency units through conductors 12 , 14 and 16 which lead to the grids of the radio frequency amplifier stages $RFT1-1$, $RFT1-2$, $RFT2-1$, $RFT2-2$, etc. of Figure 5.

To change the time constants on the various 50 automatic gain control circuits, switches TCS and condensers TC , Figure 6, are provided.

For a full diversity telephony connection, switches $1A$, $2A$ and $3A$ are thrown to the up position so that the following contacts are 55 closed: $1A1$, $1A2$, $2A1$, $2A2$, $3A1$ and $3A2$, the switch $4A$ being moved so that contacts $4A1$ and $4A2$ are closed or in their normal position. To measure the combined outputs, the contacts $4A3$, $4A4$ are closed, as a consequence of which the combined output is made manifest in the signal indicator or milliammeter $MA-4$. The combined telephony signal will appear in conductor 20 and this is fed to a common audio frequency amplifier such as $AF-1$ or $AF-2$ of Figure 1, which 60 will be described in greater detail hereinafter. The automatic gain control with the full diversity telephony connection is obtained from conductor 22 which, it will be found, is connected to the automatic gain control leads 12 , 14 and 16 65 leading to the radio frequency tubes of the radio frequency units $RF1$, $RF2$ and $RF3$ of Figure 1.

Now let it be supposed that it is desired to connect two receivers for diversity telegraphy on a common signal and to have the other receiver 75

connected so as to receive a different telephonic signal. For example, let it be assumed that receiver 3 is to supply the telephonic signal and that receivers 1 and 2 are to be combined in diversity fashion for a telegraphic signal. Contacts 3A1 and 3A2 of switch 3A are closed and with the understanding that contacts 4A1 and 4A2 of switch 4A are normally closed, it should be clear that on conductor 28 the audio frequency signal will be impressed upon an audio frequency amplifier such as AF1 of Figure 1. The automatic gain control voltage will be returned for receiver 3 through lead 22, contacts 3A1, now closed, and thence over conductor 16 to the radio frequency tubes of receiver 3. To connect receivers 1 and 2 for telegraphic diversity on a common signal, switch contacts 1B1 and 1B2 of switch 1B are closed, as are contacts 2B1 and 2B2 of switch 2B. The combined telegraphic signal is then fed out over conductor 8 to a suitable tone keyer such as TKO—2 of Figure 1 and the automatic gain control voltage is brought in over conductor 10 and fed to the radio frequency tubes of receivers 1 and 2 over conductors 12 and 14.

Attention is directed to the fact that in Figure 6 there is switching to three audio frequency amplifier units and to one tone keyer unit. If desired, the designation given in the brackets 30 may be used so that the switching of Figure 6 will correspond in every detail to the two audio frequency amplifiers and two tone keyers and oscillators provided in Figure 1.

While it is preferable to have mechanically 35 interlocked A and B switches, this interlocking is not essential since a reasonably skilled operator will soon learn the various positions necessary to prevent mix-up of signals.

Should it be desired that the three receivers 40 operate on separate signals; for example #1 on a telephony signal, #2 on a different telephony signal and #3 on a telegraphic signal, briefly the following connections may be made: Throw switch 1A to its up position so that contacts 1A1 and 1A2 are closed; throw switch 2A to its down position so that contacts 2A1 and 2A2 are closed; and finally, actuate switch 3B to its down position so that contacts 3B1 and 3B2 are closed.

The wiring diagram of an audio frequency amplifier such as AF1 or AF2 of Figure 1 is given 50 in Figure 7. Conductors such as 30 and 32 of Figure 6 are connected directly to the terminals 38', 32' of Figure 7. Automatic gain control voltage is provided with a suitable time constant 55 of operation by the time constant circuit TC1. Audio frequency telephonic signal is fed to the two stage resistance coupled amplifier AFRA and thence to a suitable output circuit, as indicated in Figure 7. In the case of diversity reception 60 for telephonic signals, the combined outputs of the diode detectors are, of course, fed into terminal 30'. The output of the audio frequency resistance coupled amplifier AFRA of Figure 7 may be utilized in a loudspeaker or fed to suitable 65 circuits for radio rebroadcasting.

A tone keyer oscillator such as TKO—1 of Figure 1 is illustrated in greater detail in Figure 8. Referring to Figure 8, the contacts 8' and 10' may be connected respectively to the leads 8 and 70 10 of Figure 6. The telegraphic output from 1, 2 or 3 of the diode detectors is fed in at the contact 8' and in the presence of a signal current flow through the tube 40 is cut off. As a consequence, the plate lead 42 no longer maintains 75 the grids of tubes 44 at a cut-off value, but

permits oscillations from a tone source 46 to be amplified by the tubes 44 and eventually fed into a transmission line TL. This tone is fed to some distant rectifier, for example, at some central receiving point, and the rectifier 50 operates a 5 suitable recorder 54. In the absence of signal, current flow through tube 40 will cause such a high negative bias to be impressed upon the grids of tubes 44 that tone from source 46 will not be fed into the transmission line TL. 10

The time control circuit TC8 controls the time constant of the voltage fed back through contact 10' of Figure 8 and conductor 10 of Figure 6.

However, during code signaling, it is undesirable to have the amplification factor of the radio 15 frequency amplifiers high during spacing periods, for this tends to raise the noise level. To remove the automatic volume or gain control at such intervals, tube 60 and its associated circuits are provided. Tube 60 operates in such a way that 20 during the period of no signal, the plate current flow reduces the amplification factor of the radio frequency amplifiers. In the presence of signal, however, tube 60 becomes blocked and is rendered useless so that only the rectified signal 25 provides its own automatic gain control voltage over the conductor 10. The foregoing circuit is more fully described and claimed in the copending application of R. L. Hollingsworth, Serial No. 732,565, filed June 27, 1934, and the circuit for 30 switching from the narrow band intermediate frequency amplifier to the wide band intermediate frequency amplifier and vice versa of Figure 5 is described and claimed more fully in my U. S. Patent 2,078,769, granted April 27, 1937 and in 35 my copending application Serial No. 699,318, filed November 23, 1933.

Figure 9 illustrates a suitable monitoring arrangement for the present diversity system. With the arrangement illustrated in Figure 9 it is possible to monitor the audio frequency amplifiers and the various keying circuits. The monitor switches of Figure 9 are of the same type as the diversity switches of Figure 6. Earphones are connected to the monitor jacks 70, 72 which, in turn, are connected to the monitoring switches M1, M2, M3, M4. The monitor switches are connected to the outputs of the various units and are not connected in parallel to the diversity switches. For example, the leads marked AF1 are connected across the output terminals marked "output" of Figure 7. In the same way, the leads marked "keyer" are connected to the output terminals, so marked, of Figure 8. The leads marked "IF" are connected to the output of a 50 detector which is supplied partially with the energy coming from such intermediate frequency amplifiers as NFA—1 and WFA—1 of Figure 5 and with energy from a local heterodyning oscillator. Such monitoring, when using leads marked "IF", serves admirably well in checking the tuning of the radio frequency oscillators, and for aural reception of slow speed telegraphic signals. A rectifier type of volt meter RTV, shown 55 in Figure 9, is provided with an on-off switch OOS to indicate the strengths of the various monitored signals. This is used particularly for 60 checking and adjusting the strength of telephone or keyed tone signals supplied to the lines leading to central offices or to broadcast control 65 centers.

What I claim is:

1. Receiving apparatus comprising a plurality of antennas, a separate radio frequency amplifying and heterodyning unit connected to each an- 75

tenna, rectifiers for separately rectifying the output of each of said units, a plurality of translating devices, and control switches for feeding all of the rectified energy into one of said translating devices and, at will, for separately feeding the rectified energy into different translating devices, or for feeding the rectified outputs of a pair of rectifiers into one translating device and the rectified output of another rectifier into a different translating device.

2. Apparatus as claimed in claim 1, characterized by the fact that each of said units includes wide and narrow band circuits, and means to feed the energy derived from the antennas selectively through said circuits.

3. Receiving apparatus comprising a plurality of antennas, a separate radio frequency amplifying unit connected to each antenna, rectifiers for separately rectifying the output of each of said units, a plurality of translating devices and a control switch for feeding all of the rectified energy into one of said translating devices and, at will, for separately feeding the rectified energy into different translating devices, or for feeding the rectified outputs of a pair of rectifiers into

one translating device and the rectified output of another rectifier into a different translating device.

4. Apparatus as claimed in claim 3, characterized by the fact that each of said units includes wide and narrow band circuits, and means to feed the energy derived from the antennas selectively through said circuits. 5

5. Receiving apparatus comprising a plurality of antennas, a separate radio frequency amplifying and heterodyning unit connected to each antenna, rectifiers for separately rectifying the output of each of said units, a plurality of filter units of different band pass characteristics and means operable at will for causing the energy 10 from one or more of said rectifying units to be fed through a selected one of said filter units. 15

6. Apparatus according to claim 5 and having means for feeding to one of said filter units the combined energies derived from different ones of said antennas, while simultaneously feeding to another of said filter units the energy derived solely from still another of said antennas. 20

JOHN B. MOORE. 25
